ASH TRAY OR SIMILAR ARTICLE

William H. Rodefeld, Wayne Township,
Wayne County, Ind.

Application December 7, 1954, Serial No. 33,435

Term of patent 14 years

(Cl. D85—2)

FIG. 1.

FIG. 2.

To all whom it may concern:

Be it known that I, William H. Rodefeld, a citizen of the United States and a resident of Wayne Township, in the county of Wayne and State of Indiana, have invented a new, original, and ornamental Design for an Ash Tray or Similar Article, of which the following is a specification, reference being had to the accompanying drawing, forming part thereof.

I claim:

The ornamental design for an ash tray or similar article, as shown.
